US00D942992S

(12) **United States Design Patent** (10) Patent No.: **US D942,992 S**
(45) Date of Patent: ** *Feb. 8, 2022

(54) **DISPLAY SCREEN WITH A GRAPHICAL USER INTERFACE**

(71) Applicant: **Facebook, Inc.**, Menlo Park, CA (US)

(72) Inventor: **Debashish Paul**, Sunnyvale, CA (US)

(73) Assignee: **Facebook, Inc.**, Menlo Park, CA (US)

(*) Notice: This patent is subject to a terminal disclaimer.

(**) Term: **15 Years**

(21) Appl. No.: **29/731,785**

(22) Filed: **Apr. 17, 2020**

Related U.S. Application Data

(62) Division of application No. 29/631,419, filed on Dec. 29, 2017, now Pat. No. Des. 884,719.

(57) **CLAIM**

The ornamental design for a display screen with a graphical user interface, as shown and described.

DESCRIPTION

The FIGURE is a front view of a display screen with a graphical user interface showing the new design.

The broken line showing of a display screen with a graphical user interface is included for the purpose of showing portions of the article which form no part of the claim.
